PICKING MECHANISM AND PICKER STICK
THEREFORWilliam A. Blanchard, Millbury, Mass., assignor
to Crompton & Knowles Loom Works, Worcester,
Mass., a corporation of Massachusetts

Application July 3, 1948, Serial No. 36,934

3 Claims. (Cl. 139—157)

1

This invention relates to improvements in picking mechanism for looms and it is the general object of the invention to provide an improved preferably tubular picker stick made in stepped sections to provide the customary taper.

Picker sticks are customarily made of wood which is subject to natural variations in strength, grain, etc., resulting in a high percentage of breakage. It is an important object of the present invention to provide a picker stick which is preferably metallic and tubular and having provision at its lower end for pivotal mounting and at its upper end for engagement with the shuttle picker.

Picker sticks are generally relatively wide and thick at their lower ends and taper toward their upper ends to provide resilience and also fit that part of the picking mechanism engaging the shuttle. It is a further object of the present invention to provide a picker stick which will have a taper resulting from making the tube in a series of stepped sections, the sections diminishing in both width and thickness from the bottom to the top of the stick.

It is always necessary to provide some means for applying power to the picker stick and it is a further object of the invention to provide a lug strap support means which will be held against downward movement relatively to the stick by a shoulder or step on one of the edges of the stick. The picker stick and support means have mutually engaging shoulders or steps which fix the vertical position of the support.

In order to permit vertical adjustment of the lug strap it is a still further object of the invention to provide the support means with a lug strap engaging holder which can be adjusted along the support in the direction of the length of the stick, preferably while the shoulders of the support means and stick engage each other.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a front elevation of part of the loom having the invention applied thereto,

Fig. 2 is an enlarged vertical section on line 2—2 of Fig. 1,

Fig. 3 is a vertical section on line 3—3 of Fig. 2,

Fig. 4 is an enlarged transverse section on line 4—4 of Fig. 1,

Fig. 5 is an enlarged horizontal section on line 5—5 of Fig. 1, and

2

Fig. 5 shows an enlargement of a part of Fig. 3.

Referring particularly to Fig. 1, the loom frame 10 supports a lay 11 which is driven by a top or crank shaft 12 having secured thereto a gear 13. The latter meshes with another gear 14 on the bottom shaft 15 to which is secured a picking actuator 16 having rotatable thereon a picking roll 17. The top shaft 12 generally rotates once for each pick of the loom while the bottom shaft rotates every second pick of the loom.

A picker shaft 20 extends back and forth in the loom and is rockable in bearings one of which is shown at 21. The shaft has secured thereto a picking cam 22 which is actuated by the roll 17. Secured to the shaft 20 is a power arm 23 which extends upwardly therefrom and is attached to a sweep stick 24 the right end of which is provided with a lug strap 25.

A rocker shaft 26 parallel to shaft 15 has secured thereto a rocker iron 27 for pivotal mounting of the picker stick designated generally at P. A return spring 28 of usual construction is attached to the lower end of the stick and tends to move the latter to the position shown in Fig. 1 after a picking operation. The shuttle S is propelled by a picker 30 slidable on a picker spindle 31 secured to the lay. While Fig. 1 shows this particular means of transmitting power from the stick P to the shuttle S, the invention is not necessarily limited to a picker which slides on a spindle.

Except for the picker stick, which will be described in detail hereinafter, the matter thus far described is of common construction. Every alternate pick of the loom the roll 17 will depress the cam 22 to rock the picker shaft 20 in a counter-clockwise direction as viewed in Fig. 1 to move the lug strap 25 to the left for the purpose of propelling the shuttle S to the opposite or left hand side of the loom. On the next pick of the loom mechanism similar to that shown in Fig. 1, but located at the opposite side of the loom, returns the shuttle.

In carrying the invention into effect the picker stick is preferably constructed of tubular form and metallic and is stepped from its lower to its upper end in such a way as to provide the general taper shown for instance in Fig. 1. The stick P is preferably though not necessarily formed as a seamless tube the wall of which, designated generally at 35, is sufficiently thick to provide adequate strength and resilience. The stick has outer and inner edges or edge walls 36 and 37, respectively, and front and back sides or side walls 38 and 39, respectively. These edges and walls are continuous from the bottom to the top of the stick but are provided with steps or shoulders so that each section of the

stick is narrower and thinner than the one below it. The walls are preferably though not necessarily of uniform thickness. In Fig. 1 six sections are shown and are indicated at 40-45, section 40 having maximum width and thickness and section 45 being narrower and thinner than any of the other sections.

At the point of juncture between two adjacent sections shoulders or steps are formed, the steps on the edges 36 and 37 being designated respectively at 48 and 49, respectively. These steps or shoulders face upwardly because of the direction in which the picker stick tapers, and set off the various sections of the stick.

In order to provide an operative connection between the lug strap 25 and the picker stick P there is provided a lug strap support means shown more particularly in Figs. 3 to 6, and designated generally at 50. The support 50 is provided with a vertically extending body 51 formed intermediate its ends with a shoulder 52 which faces downwardly. The upper end 53 of the support has extending laterally therefrom and inwardly toward the loom a pair of wings or arms 55, and the lower end 54 of the support has another pair of wings or arms 56 similar to wings 55. In order to provide means for holding the support to the picker stick each pair of arms is provided with a clamping bolt. As shown in Fig. 3 an upper bolt or screw 60 extends through slots 61 in arms 55, while a second bolt or screw 62 extends through slots 63 in the lower arms 56. The slots 61 and 63 are horizontal and are of such length as to permit the bolts 60 and 62 to be moved in close to engage the inner edge 37 of the picker stick for the purpose of holding the support 50 in the position shown in Fig. 3 with shoulder 52 engaging one of the shoulders 48 on the outer edge 36 of the stick to prevent the support from slipping down along the stick. The lug strap extends around the support 50 as shown particularly in Fig. 5.

In order that the position of the lug strap may be supported and be adjustable vertically or along the length of the picker stick there is provided a holder 65 having a vertical part 66 and an offset foot 67 on which the lug strap 25 rests. The upper end of the holder is provided with a vertical slot 68 which receives a screw 69 tapped into the holder 65 and serving to maintain the holder in any desired vertical position.

The lower end of the picker stick is provided with an internal plug 70 which may be of any material, such as wood or a light-weight metal such as aluminum or magnesium. Bearing hole 71 is drilled through the front and back walls of the low section 40 and also through the plug to receive a supporting or pivot pin or stud 72 mounted on the rocker iron 27. A screw 75 may be tapped into the plug 70 to hold a strap 76 connected to the aforesaid spring 28.

In operation, the lug strap acting through the holder 65 and support 50 will cause the picker stick to move or sweep to the left as viewed in Fig. 1 to effect picking of the shuttle S as roll 17 engages cam 22. If it be desired to adjust the power of the pick the holder 65 can be changed by loosening the screw 69 and sliding the holder vertically along the support member 50. This adjustment can be made without disturbing the screws 60 and 62 and while a shoulder on the picker stick engages the shoulder 52 of the support 50.

From the foregoing it will be seen that I have provided a simple form of picker stick made of 75

stepped sections which diminish in width and thickness from the bottom to the top thereof when the stick is in operating position. The stick has steps or shoulders between its sections and one of these steps is utilized to engage the shoulder 52 of the support member 50, thereby preventing downward movement of the holder with respect to the stick. The sections are made progressively narrower and thinner from bottom to top of the stick so that the latter is more resilient at its upper end than at its lower end, and each section preferably though not necessarily has parallel edges and back and front faces. The stick is made preferably of a seamless metallic tube, although so far as certain features of the invention are concerned the stick need not be seamless or formed as a single tube throughout its length. Also, the holder 65 is adjustable vertically along the support member 50 and the adjustment of the holder can be made without disturbing the engagement of the shoulder on the support and the shoulder on the stick which it engages.

Having thus described the invention, it will be seen that changes and modifications of the foregoing specific disclosure may be made without departing from the spirit and scope of the invention.

What is claimed as new is:

1. In picking mechanism for a loom having a lug strap, a picker stick having sections of progressively diminishing width from the lower end to the upper end thereof, said stick having upwardly facing shoulders between the sections thereof, a support engaging certain of said sections and having a downwardly facing shoulder engaging one of the shoulders on the picker stick, and a holder for the lug strap on said support.

2. In picking mechanism for a loom having a lug strap, a picker stick having sections of progressively diminishing width from the lower end to the upper end thereof, said stick having upwardly facing shoulders between the sections thereof, a support engaging adjacent sections of the picker stick and having a downwardly facing shoulder, means holding the support on said picker stick with said shoulders engaging each other, and a holder for the lug strap on said support.

3. In picking mechanism for a loom having a lug strap, a picker stick having sections of progressively diminishing width from the lower end to the upper end thereof, said stick having upwardly facing shoulders between the sections thereof, a support engaging certain of said sections and having a downwardly facing shoulder engaging one of the shoulders on the picker stick, a holder for the lug strap, and a connection between the support and holder affording adjustment of the latter relatively to the support in the direction of the length of the picker stick while said shoulders are in mutual engagement.
